UNITED STATES PATENT OFFICE.

OLIVE BLAKELEY, OF LURAY, MISSOURI.

WALL-PAPER-DISPLAY RACK.

SPECIFICATION forming part of Letters Patent No. 699,478, dated May 6, 1902.

Application filed November 1, 1901. Serial No. 80,803. (No model.)

To all whom it may concern:

Be it known that I, OLIVE BLAKELEY, a citizen of the United States, residing at Luray, in the county of Clark and State of Missouri, have invented a new and useful Improvement in Wall-Paper-Display Racks, of which the following is a specification.

My invention relates to an improvement in wall-paper-display racks, the primary object 10 being to display a large assortment of different samples in convenient and artistic arrangement within easy reach of the salesman or customer without the necessity of changing his or their position while inspecting the 15 entire complement of samples exhibited.

With this object in view my invention consists in certain novel features of construction and combinations of parts, which will be hereinafter described, and pointed out in the 20 claims.

In the accompanying drawings, Figure 1 is a view in perspective of my improved wall-paper-display rack. Fig. 2 is a vertical section. Fig. 3 is a plan view, and Figs. 4 and 25 5 are details.

The base comprises several legs 1 1, preferably four in number, rigidly secured together at the top and bottom by suitable plates 2 2. A bolt 3, with a threaded lower 30 end, is fastened securely to the base by means of a nut 4, screwed on the lower end, and a collar 5, which rests upon the top of the base.

The rack consists, preferably, of a triangular frame 6 at the bottom and three side 35 frames 7 7 7, of rectangular form, erected upon the triangular bottom frame 6, whereon they are secured with their beveled edges 8 8 against each other by means of bolts 9 9 9. The upper ends of these rectangular side 40 frames are secured together by means of plates 10 10 10, which plates may be fast at both ends or pivoted at one end, as shown, and removably secured to pins 11 11 11, which enter holes 12 12 12, formed in the plates to receive them. In this way the framework of the rack can be readily dismantled for shipping or storing and put together again with equal facility. Two spiders 13 and 14 are secured to the bottom frame 6, one to the lower 45 surface thereof and extending downwardly, and the other one to the upper surface, so as to project upwardly into the center of the

rack. In the centers of these two spiders holes 15 15 are made to receive the bolt 3, which projects upwardly from the base and 55 about which the framework of the rack revolves. At each side of the rectangular side frames metal strips 16 and 17 are attached by plates or equivalent means 18 18. The left-hand strip preferably is provided with 60 a series of holes 19 19, whereas the right-hand strip of each pair is provided with a corresponding number of open slots or notches 20 20, which latter open upwardly. While the number of these holes and notches is of little 65 consequence and may be varied, it is my purpose to have fifteen of each. In these holes or notches shafts 21 21 are revolvably and 70 removably supported, and the latter each carry a roll of paper to be displayed thereon. The 75 shafts themselves may be variously constructed and preferably have smaller diameters at their ends to form bearings to turn in the holes and notches. One end of each shaft—namely, the one in the notch—is preferably squared 80 or angular to receive a crank 22 thereon, by which the shaft may be turned to rewind a roll of paper which has been pulled out for display. Spring-actuated latches 23 23 are pivoted in proximity to these notches, and 85 the latches themselves have notches 24 24 therein to receive and bear down upon the ends of the shafts to retain them in their notches and prevent the shafts from turning accidentally until positively turned by the 90 crank. These latches may be variously constructed; and it is desirable that their free ends should protrude beyond the outer edge of the strip to which they are pivoted, so that the shaft or roller can be inserted in the notch 95 by merely forcing it upward against the latch and then after the latch is pushed aside dropped into the notch. In the same way it is quite as convenient to remove a shaft or roller, as the latches yield easily to outward 100 pressure, after which the rollers may be pulled out endwise. The shafts preferably each have three springs 25 25 25, inclining in one direction and disposed at opposite points on the surface of the shaft, their object being to keep the paper from turning on the shafts.

By reason of the triangular formation of the display-rack access to the ends of the shafts or rollers can be easily had. Likewise

the arrangement is excellent for the display of a large number of different patterns, inasmuch as provision is made for displaying simultaneously in the neighborhood of forty-five different styles of paper.

It is obvious, of course, that the material composing my improved display-rack might be varied, as well as the dimensions, none of which have been specified, and it is evident that slight changes might be made in the form and arrangement of the several parts described without departing from the spirit and scope of my invention, and hence I do not wish to limit myself to the exact construction herein set forth; but,

Having fully described my invention, what I claim as new, and desire to secure by Letters Patent, is—

1. In a wall-paper-display rack, the combination with a base, of a rack revolvably supported thereon, said rack composed of detachable sections, and a plurality of rolls detachably locked and revolvably supported in

each section, so that the entire rack may be dismantled for packing or shipping and each rack-section still retain its full complement of rolls.

2. In a wall-paper-display rack, the combination with a base having a rod secured thereto and projecting upward therefrom, of a frame comprising a bottom piece and side frame, and a pair of spiders secured to the bottom piece, one projecting downwardly and the other upwardly into the space in the side frame, said spiders each having a hole in the center wherein to receive the rod or bolt which projects upwardly from the base and upon which the rack turns.

In testimony whereof I have signed this specification in the presence of two subscribing witnesses.

OLIVE BLAKELEY.
